UNITED STATES PATENT OFFICE.

SAMUEL WILSON, OF CHICAGO, ILLINOIS.

OVERHEAD-TROLLEY SYSTEM.

1,189,895.

Specification of Letters Patent. Patented July 4, 1916.

Application filed May 6, 1915. Serial No. 28,200.

To all whom it may concern:

Be it known that I, SAMUEL WILSON, a citizen of the United States, residing at Chicago, in the county of Cook, and State 5 of Illinois, have invented certain new and useful Improvements in Overhead-Trolley Systems, of which the following is a specification.

This invention relates to improvements in 10 overhead trolley systems for electric railways so constructed that the trolley wheel will not leave the supply wire at line intersections or other points.

With the foregoing and other objects in 15 view the invention consists in the combination and arrangement of parts to be herein-after fully described in the following specification, pointed out in the claim and illustrated in the accompanying drawings which 20 form a part of said specification and in which—

Figure 1 is a side view of a portion of the supply wire showing its arch at a crossing and the particular type of trolley used. Fig. 25 2 is a similar view with the trolley in an altered position. Fig. 3 is a rear view of the trolley and is taken on line 3—3 of Fig. 1. Fig. 4 is an inverted plan view on line 4—4 of Fig. 1. Fig. 5 is a sectional view of 30 a crossing where a plurality of supply wires meet and cross. Fig. 6 is a section taken on line 6—6 of Fig. 2. Fig. 7 is a longitudinal sectional view through a portion of the feed wire adjacent the crossing. Fig. 8 is a similar view showing a modified arch.

Like reference characters indicate corresponding parts throughout the several views.

The reference numeral 1 designates the supply wire which at all intersections or 40 wire crossings is arched as at 2. I prefer to have the arches at all crossings formed of pieces of wire mortised at each end as at 3 to receive tenons 4 of the main supply wire; said tenons being of smaller diameter 45 than the wire 1. The arched piece 2 is provided with a set screw 5 adapted to engage the tenon 4 and retain it in an adjusted position in the said arched piece. This construction permits the formation of a narrow 50 or wide arch as desired or of the change of one form of arch to the other readily. Circular collars 6, also made of wire, may be placed about the portion of the tenon 4 between the main wire and the end of the arch 55 to properly fill out said tongue.

My trolley comprises the pole 7 pivotally carried in bearings 8 arranged upon the base 9 which is pivotally carried upon the roof of the car 10; said pole being provided with the cross piece 11 to which the anchor cord 60 11^a is secured and to which springs 12, 12 are also secured that connect with the tension poles 13, 13 also pivotally carried upon the said base 9. The upper end of the pole 7 is bifurcated to receive the shaft 14 that 65 carries the trolley wheel 15 and that also carries the arched frame 16, 16 in which the guide spools 17, 18 are terminally carried. The trolley wheel 15 is formed with a 70 grooved periphery to engage with the supply wire and the spools 17, 18 arranged in the front and rear of the wheel 15 permit the device to pass over a crossing, such as is illustrated in Figs. 5 and 6, without danger of jumping the wire. In Fig. 2 the trolley 75 wheel is shown just about to pass the crossing and in Fig. 1 the trolley wheel has just left the supply wire and the spool 18 has engaged it and will ride along it until the wheel 15 picks it up again. The 80 tension poles 13 and springs 12 cause the spools 17, 18 to pick up the supply wire as soon as the trolley wheel leaves it.

What is claimed is:—

The combination with an electrically propelled vehicle, of an elevated supply wire 85 formed with extensible arched portions at its intersection with other supply wires, a base pivotally carried by the vehicle, a trolley pole carried by said base, tension 90 poles carried by said base and operatively connected to said trolley pole, a trolley wheel carried by said trolley pole, a frame fast upon the axle of said trolley wheel, and spools carried by said frame and positioned 95 in advance and in the rear of said trolley wheel for engagement with said supply wire, through the action of said tension poles, while said trolley wheel is passing the arched portions of said supply wire. 100

In testimony that I claim the foregoing as my own I have hereto affixed my signature in the presence of two subscribing witnesses.

SAMUEL WILSON.
